COMBINED COVER AND CARRIER FOR A PORTABLE WASHER AND WRINGER

Harold F. Brogdon, Grand Rapids, Mich., assignor, by mesne assignments, to Automatic Music, Inc., Grand Rapids, Mich., a corporation of Delaware

Filed June 9, 1958, Ser. No. 51,272

Term of patent 3½ years

(Cl. D49—1)

Figure 1 is a perspective view showing one side of a combined cover and carrier for a portable washer and wringer embodying my new design;

I claim:

The ornamental design for a combined cover and carrier for a portable washer and wringer, as shown.
